UNITED STATES PATENT OFFICE.

JOSEPH A. LYMBURNER, OF SAN FRANCISCO, CALIFORNIA.

WAVE MOTOR.

Application filed November 19, 1921. Serial No. 516,369.

To all whom it may concern:

Be it known that I, JOSEPH A. LYMBURNER, a citizen of the United States, residing at San Francisco, in the county of San Francisco and State of California, have invented certain new and useful Improvements in Wave Motors, of which the following is a specification.

This invention relates to wave motors, and 10 has for one of its objects to produce a device of this character adapted to be supported upon the bottom of the sea or other body of water in which waves are liable to be produced by the wind, and including a float 15 arranged to be elevated and depressed by the waves, and means whereby the vertical movement of the float is utilized to store up energy for future use, or to produce motion which may be transmitted to air pumps or 20 other suitable devices.

Another object of the invention is to provide a device of this character with a movable and adjustable shield or guard whereby abnormal force of the waves is prevented 25 from displacing or otherwise interfering with the operation of the float.

With these and other objects in view, the invention consists in certain novel features of construction as hereinafter shown and 30 described and then specifically pointed out in the claims, and in the drawings illustrative of the preferred embodiment of the invention.

Figure 1 is a side elevation, partly in section, of the improved apparatus.

Fig. 2 is a plan view of the same.

Fig. 3 is a transverse section on the line 3—3 of Fig. 1.

Fig. 4 is a transverse section on the line 40 4—4 of Fig. 1.

Fig. 5 is a detached view, illustrating a modified form of the guide rollers.

The improved apparatus includes a plurality of combined guides and supporting 45 posts 10 rigidly supported or anchored in a relatively heavy bed, represented conventionally at 11, of concrete or the like, on the bottom of the sea or other body of water in which waves are produced by the action 50 of the wind. The posts are arranged to inclose a prescribed area, and any required number may be employed and spaced at any required distance, but for the purpose of illustration, five of the posts are shown.

55 The posts may be of any length and of any

suitable form or material but are preferably of channel steel, as shown.

Encompassing the posts 10 at their upper ends and rigidly connected thereto is a band 12, while a similar band 13 encompasses the 60 posts in spaced relation to the upper band 12, and is rigidly coupled thereto preferably by riveting. The bands 12 and 13 and the posts 10 are reinforced by diagonal braces 14 connected respectively to the bands, as 65 shown.

Bearing upon the posts 10 and the upper band 12, is a platform structure formed of sill members 15 and an annular floor portion 16, the sill members being supported 70 and reinforced from the lower band 13 by braces 17.

A plurality of devices adapted to be actuated by the power developed by the apparatus, for instance air pumps, are supported 75 on the platform 16, and represented conventionally at 18.

A float device of suitable construction and represented conventionally at 19, is located within the area defined by the posts, and 80 provided with guide rollers 20 operating in the channels of the posts, as shown. By this means the float is movable vertically with the minimum of friction and held from displacement laterally.

In Fig. 1, the rollers are single, while in Fig. 5 the rollers are double or of the "twin" class. Either form may be employed as required.

Attached to the float 19 and extending 90 above the same are gear rack bars 21, preferably midway between each pair of the posts 10, and coupled and supported at their upper ends by braces 22.

Mounted upon the platform 16 adjacent 95 each of the rack bars 21, is a standard 23, and mounted for rotation in each standard is a shaft 24, each shaft carrying a gear wheel 25 to be engaged by the gear racks, and a crank arm 26 coupled respectively to the 100 piston rods 27 of the pump devices 18 by connecting rods 28. By this arrangement it will be obvious that as the float is moved vertically, motion will be transmitted thereby to the pump pistons.

Slidably disposed upon the external faces of the posts 10 are shield plates 29, each provided with suitable guide rollers 30 engaging the posts 10 and thereby movable 105 vertically of the posts with the minimum of 110

friction. The members 29 are adapted to be adjusted upon the posts to unitedly form a shield or guard to the float in event of the lateral force of the waves being abnormally strong, or liable to displace the float laterally, or in event of the lateral force of the waves being greater than their lifting force.

Any suitable means may be employed to control the movement of the shield members, but for the purpose of illustration pull cables 31 are shown attached to the members 29 and operating over guide sheaves 32 attached to the band 13.

The supporting members for the posts and platform must be of ample strength and rigidity to withstand the pressure and shock of the waves, and may be of any form or proportion, depending on the location and the force of the waves where the device is located.

The pumps may be employed to store up the air in receptacles for future use.

The preferred embodiment of the invention is disclosed in the drawings and set forth in the specification, but it will be understood that modifications within the scope of the claimed invention may be made in the

construction without departing from the principle of the invention or sacrificing any of its advantages.

Having thus described the invention, what is claimed as new is:—

1. In a wave motor, a plurality of stationary guide posts in spaced relation and defining a prescribed area, a float movable 35 within the area defined by said posts and guided thereby, means for transmitting motion from said float, shield members bearing upon the outer faces of said posts, guide rollers carried by said shield devices and engaging the guide posts, and means for vertically adjusting said shield members.

2. In a wave motor, a plurality of stationary guide posts in spaced relation and defining a prescribed area, a float movable 45 within the area defined by said posts and guided thereby, means for transmitting motion from said float, shield members encompassing said posts, and means for vertically adjusting said shield members.

In testimony whereof, I affix my signature hereto.

JOSEPH A. LYMBURNER.
